UNITED STATES PATENT OFFICE.

EDGAR H. CROSSEN, OF FRANKLIN, PENNSYLVANIA.

OIL-ENGINE.

1,338,289.

Specification of Letters Patent. Patented Apr. 27, 1920.

Original application filed June 17, 1918, Serial No. 240,408. Divided and this application filed May 16, 1918. Serial No. 297,684.

To all whom it may concern:

Be it known that I, EDGAR H. CROSSEN, citizen of the United States, residing at Franklin, in the county of Venango and 5 State of Pennsylvania, have invented certain new and useful Improvements in Oil-Engines, of which the following is a specification.

This invention relates to that class of internal combustion motors that is especially adapted to utilize as fuel, certain grades of petroleum or oil that is too heavy for use with carbureters.

In the accompanying drawings I have 15 shown the embodiment of my inventive idea in a two-cycle, three-port horizontal engine; the drawings are, however, illustrative merely, of one form of embodiment which I have found, by actual reduction to practice to be satisfactory. The invention is 20 equally applicable to other types of two cycle, as well as to four-cycle engines.

In said drawings:

Figure 1 is a central, vertical, longitudinal section through the cylinder and combustion chamber of an engine constructed in accordance with my invention; the piston is shown in this view at the rear end of its stroke or point of maximum compression, 25 this being also the position at which air enters the pump chamber.

Fig. 2 is also a central, vertical, longitudinal section through the cylinder and combustion chamber of my improved motor, the piston being shown in this view at the forward end of its stroke, this being the position in which the fuel is transferred from the pump chamber to the expansion chamber of the cylinder.

Fig. 3 is an elevation of the outer end of the cylinder head with the cap removed.

Fig. 4 is a side elevation of the cylinder head with the upper half in section.

Fig. 5 is an elevation of the inner end of 5 the cylinder head.

Fig. 6 is a central, vertical section of a modified form of cylinder head and combustion chamber.

Fig. 7 is an elevation of the inner face of 0 the head shown in Fig. 6.

I will now describe the construction illustrated in the drawings with particular reference to the novel features there shown which

are, the combustion chamber and the surrounding structure immediately associated 55 and coöperating therewith.

Within the head 1 of the cylinder, I provide a combustion chamber 2, the inner end of which is provided with one or more ports 3, 4, which are positioned adjacent to and 60 communicate with the expansion chamber 5 of the cylinder which is at the rearward face of the piston 6.

Said combustion chamber 2 is completely surrounded by the water-jacketed walls of 65 said head 1, with the exception of the communicating ports 3' 4' which form inter-communicating means between said combustion chamber 2 and said expansion chamber 70 5.

The outer end of said head 1 is provided with a removable cap 7 for convenience of assembly and easy access to said combustion chamber. Said combustion chamber 2 is secured in position within head 1 and con- 75

centric with the surrounding walls thereof, by means of the oppositely-disposed lugs 8, 8, for the reception of which, two corresponding recesses are provided in the joint face of said head 1. Screws 9 pass through 80 said lugs 8 into the adjacent walls of said head and serve to hold said chamber 2 in position. Said combustion chamber is, as above stated, concentric with the adjacent surrounding walls of head 1 and is of 85 smaller diameter than the inclosing chamber therefor in said head so that an intervening space 10 is formed between the juxtaposed walls of said chamber and head. Said space 10 is accessible to the gases of combus- 90 tion, the purpose of this provision being to maintain said combustion chamber at a high and even heat throughout its whole extent by subjecting substantially the whole of the superficial area to the heat of combustion; 95 whereby the fuel oil, as it enters said chamber is instantly, and as nearly as possible, completely vaporized.

The fuel oil is injected into said combustion chamber from the rear thereof through 100 a suitable nozzle 11 and with sufficient force to project it horizontally across said chamber 2 into contact with the inner wall thereof, and, inasmuch as the walls of said chamber are maintained at a red heat the oil 105 is usually completely vaporized before it

comes into contact with the walls of said chamber, but, in case it is not fully vaporized in passing across said chamber 2, any unvaporized portion is converted into vapor when it strikes the wall of said combustion chamber opposite to the side at which it enters—see Fig. 1.

The fuel oil may be supplied to the combustion chamber by means of any suitable pump, the action of which is so timed that the oil will be injected into the combustion chamber at substantially the moment of highest compression, as shown in Fig. 1. The port 11 through the rear wall of the combustion chamber, adjacent to said nozzle 11 may be any desired size which best suits the purpose, and it may be large enough to serve as a cleaning-out port when cap 7 is removed.

20 Provision is made for starting the engine in the following manner:

In the lower part of combustion chamber compartment of head 1, is formed an oil-receiving pocket 12, and into said pocket is introduced the open end of a retort 13 which is a tubular element closed at its lower end; said retort is suitably inclosed by a hood 14, having an opening 15 through which the flame of a torch or other suitably generated heat may be directed for the purpose of heating said retort. When the engine is to be started, said retort is first suitably heated, then oil is supplied to the combustion chamber through the nozzle 11; the oil thus supplied drains into said heated retort and is vaporized thus forming the combustible element of the fuel, then as the piston is brought to its compression position and the air compressed thereby forms an explosive mixture with said vapor, an explosion occurs which starts the engine running, and thereafter it will continue to operate in the normal way.

In Figs. 6 and 7 I have shown a modified form of cylinder head and combustion chamber. It will be readily noted by an inspection of Fig. 6 that the combustion chamber 2 and the inclosing portion of head 1 are here shown to have the form of a truncated cone with the smaller end thereof disposed outwardly. This form of head and combustion chamber has but one intercommunicating port 3, 3', which is located at the lowermost part of said combustion chamber and in alignment with said oil receiving-pocket 12.

It will be noted that distinction is made between the combustion chamber 2 and the expansion chamber 5, and I wish to emphasize somewhat upon the reason for this distinction. It should be noted that, inasmuch as the combustible element of the fuel (the fuel oil) is introduced into and is practically all confined to said combustion chamber, combustion takes place within said

chamber, when, by the compressive action of the piston air is supplied thereto; the heat thus produced is imparted to the air within the expansion chamber 5 through the ports 3' 4'.

70

Because, however, of the restricted area of said ports, said impartation of heat is somewhat prolonged, and the effect of said prolongation is an impulse upon the piston which approaches that obtained in a steam engine, and in this respect differs perceptibly from the usual impulse of internal combustion motors where the full force of the explosions acts instantaneously upon the piston. In this respect, the construction 75 herein disclosed is a material and desirable improvement over the construction shown and described in Letters Patent of the United States, No. 1,148,577 issued to me August 3, 1915. The construction here disclosed is further a material improvement over that shown in said patent in the respect that in the present construction, the fuel oil and the combustion thereof is confined to the combustion chamber 2; that if 80 any of the fuel oil enters the expansion chamber 5, or comes into contact with the walls thereof, it is only the lighter fractions which are wholly and completely combustible; for this reason no carbon is deposited 85 outside of said combustion chamber, and the piston rings do not become fouled or their efficiency reduced thereby.

95

I do not wish to be understood as claiming that all deposit of carbon is avoided 100 by my construction, but I do attain the very important and desirable advantage of confining all deposit of carbon to the combustion chamber 2, and the greater portion of this deposit forms upon that part of the 105 wall of said chamber 2 which is opposite to the nozzle 11, where it flakes off by the action of the heat and is ejected through the ports 3, 3' and out through the exhaust port of the cylinder. This is the particular object of positioning a port at the lowermost portion of said combustion chamber.

110

I am aware of the state of the art in respect to positioning the combustion chamber and it is not my purpose to broadly claim such construction or arrangement; but I believe it to be new to so construct a combustion chamber of an oil engine as to expose the entire superficial area of the 112 walls of such chamber to the heat produced by combustion; I also believe the particular construction and relative arrangement of the combustion chamber and expansion chamber here shown, to be new.

115

In the drawings which form a part hereof, I have shown an atomizer A which is especially adapted for supplying water to the expansion chamber 5, but, inasmuch as said atomizer is fully shown and described 1

120

in a co-pending application, Serial Number 297,683 the same is not here described in detail.

I claim the following:

- 5 1. An oil engine of the horizontal type comprising in combination a cylinder having a combustion chamber and an expansion chamber, water-jacketed walls surrounding and spaced from the walls of said combustion
- 10 chamber with the intervening space freely accessible to the heated gases of combustion, fuel-oil injecting means adapted to inject fuel-oil into said combustion chamber from the rearward portion thereof longitudinally across the same, and means of restricted communication between said chambers.
- 15 2. An oil engine of the horizontal type comprising in combination a cylinder provided with a combustion chamber and an expansion chamber, walls surrounding said combustion chamber and spaced from the walls thereof to form an intervening space freely accessible to the gases of combustion, means adapted to supply fuel oil to said combustion chamber through the rearward portion thereof and to project same longitudinally across said chamber, and means of restricted intercommunication between
- 20 said chambers at the lowermost portion of said combustion chamber.
- 25 3. An oil engine comprising among its elements, in combination, a combustion chamber arranged to have its superficial area subjected to the gases of combustion, an ex-

pansion chamber, and a water-jacketed wall intervening between and provided with intercommunicating means for said chambers.

4. An oil engine, of the horizontal type, comprising among its elements, in combination, a combustion chamber arranged to have substantially all of its superficial area subjected to the heat of combustion, means for injecting fuel-oil into said chamber from its rearward portion and across the same against its forward wall, an expansion chamber, a water-jacketed wall interposed between said chambers, and an inter-communicating port for said chambers, which intersects the lower peripheral wall of said combustion chamber for the purposes specified.

5. An oil engine of the horizontal type, comprising among its elements, in combination, a combustion chamber arranged to have substantially all of its superficial area subjected to the heat of combustion, an expansion chamber, water-jacketed walls surrounding and interposed between said chambers, and an intercommunicating port for said chambers, which intersects a portion of the lower peripheral wall of said combustion chamber for the purposes specified.

In testimony whereof I affix my signature in presence of two witnesses:

E. H. GROSSENBACH
